UNITED STATES PATENT OFFICE.

ANTOINE MARIUS CAVE, OF ST. ETIENNE, FRANCE.

ALKALINE ACCUMULATOR.

1,350,956.

Specification of Letters Patent. Patented Aug. 24, 1920.

Application filed November 7, 1918. Serial No. 261,532.

To all whom it may concern:

Be it known that I, ANTOINE MARIUS CAVE, a citizen of the French Republic, residing in St. Etienne, Loire, France, have 5 invented certain new and useful Improvements relating to Alkaline Accumulators, of which the following is a specification:

The greatest difficulty met hitherto in the manufacture of the electrodes of accumulators with alkaline electrolyte consists in the agglomeration of the oxids to form 10 homogeneous and sufficiently conducting masses.

The present invention consists in a method 15 of constructing these electrodes by which this difficulty is obviated.

The construction is illustrated in the accompanying drawings in which:—

Figure 1 shows respectively in front and 20 side view the central conductor or core of an electrode.

Fig. 2 illustrates the manner in which a metallic cloth is wound around the conductor.

25 Fig. 3 is a transverse section on the lines 3—3 of Fig. 2.

Fig. 4 shows respectively in front and side view a finished electrode.

30 Fig. 5 shows an arrangement of several electrodes in a frame forming together a surface of greater or less size.

Fig. 6 is a transverse section on the line 2—2 of Fig. 5.

The plate *a* forming a central conductor is 35 of nickel or of a metal suitably nickelized or covered with nickel. This plate is perforated over all its length with holes *b* which can be disposed in one or more rows, and at each end of the plate are fixed wings *c*.

40 Wound around this plate and in intimate contact with it is a metallic cloth *d* of such a length that when the cloth is folded around the plate the electrode so far formed will be of the required thickness; this cloth is formed

45 of threads of nickel or of suitable metal as stated above.

The electrode being thus prepared, all the spaces left in the cloth are filled with oxids or a suitable mixture according to the polar-

50 ity that is to be given to this electrode, the same being pasted on or otherwise applied. The whole is then covered with an insulating envelop *e* permeable to gases, and formed of fibrous vegetable or mineral tissues; this 55 envelop is kept in place by a wrapping of braids, cords or tapes *f*, formed of the same

fiber, or of asbestos, which may be reinforced by metallic threads during their manufacture, and which can be impregnated with varnish or coatings unaffected by alkalis. 60 It should be noticed that these tissues, cords or ribbons formed of vegetable fibers contract considerably in the alkaline bath which forms the electrolyte, producing in this way a pressure which may be considerable and which holds the parts close together and is 65 very advantageous for the efficient action of the electrode.

When a plate has been covered with its insulating envelop held by the cords, the wings *c* are bent down against the envelop surface so as to hold the edges thereof (Fig. 4) and the whole is submitted to the action of a press in a suitable mold to insure a still more complete contact between the oxids and the 70 metallic cloth. It is evident that this pressure might be exerted before the insulating envelop is put in place; also, that instead of the electrode being a plate it might be of cylindrical, tubular or other form.

80 In order to obtain a desired amount of active surface it is sufficient to assemble a number of electrodes, whatever may be their form, in a frame formed, for example, by side pieces *g*, and cross pieces *h* (Figs. 5 and 85 6). These frames, forming also supports, can be insulated by a suitable covering or casing, if soluble negative electrodes are used.

In this latter case the negative electrodes 90 would consist of metallic sheets, which may be corrugated or plain and be formed of any suitable metal such as zinc, but all the metals of which an oxid is soluble in alkalis are suitable if a suitable oxid is applied to the 95 positive pole.

It should be noticed that when a soluble electrode is employed it is advantageous to surround the negative plate or to prevent movement of the re-acting liquid by means 100 of porous material insensitive to alkalis and which will help to maintain the deposits on their support better than the arrangements previously known.

Having thus described the nature of the 105 said invention and the best means I know of carrying the same into practical effect, I claim:—

1. An electrode for electric accumulators, comprising in combination a central conducting metal plate having perforations 110 along its length, metallic cloth wrapped

- around and in intimate contact with the plate, active material filling the interstices in the cloth, and an insulating envelop permeable to gases covering the cloth.
5. 2. An electrode for electric accumulators, comprising in combination a central conducting metal plate having perforations along its length, metallic cloth wrapped around and in intimate contact with the plate, active material filling the interstices in the cloth, an insulating envelop permeable to gases covering the cloth, and bands of vegetable tissue enwrapping the envelop.
10. 3. An electrode for electric accumulators, comprising in combination a central conducting metal plate having perforations along its length, metallic cloth wrapped around the plate, active material filling the interstices in the cloth, an insulating envelop permeable to gases covering the cloth, bands of vegetable tissue enwrapping the envelop, and means carried by the ends of the plate adapted to hold the envelop in position on the cloth.
15. 4. An electrode for electric accumulators, comprising in combination a central conducting metal plate having perforations along its length, metallic cloth wrapped around the plate, active material filling the interstices in the cloth, an insulating envelop permeable to gases covering the cloth, bands of vegetable tissue enwrapping the envelop, and means carried by the ends of the plate adapted to hold the envelop in position on the cloth.
20. 5. In an electric accumulator a positive electrode comprising in combination a central conducting metal plate having perforations along its length, metallic cloth wrapped around the plate, active material filling the interstices in the cloth, an insulating envelop permeable to gases covering the cloth, and bands of vegetable tissue enwrapping the envelop, and reinforcing metallic threads incorporated with the tissues of the bands.
25. 6. In an electric accumulator a positive electrode comprising in combination a central conducting metal plate having perforations along its length, metallic cloth wrapped around the plate, active material filling the interstices in the cloth, an insulating envelop permeable to gases covering the cloth, and a negative electrode consisting of a metallic sheet soluble in the electrolyte in the accumulator.
30. 7. In an electric accumulator a positive electrode comprising in combination a central conducting metal plate having perforations along its length, metallic cloth wrapped around the plate, active material filling the interstices in the cloth, an insulating envelop permeable to gases covering the cloth, and a negative electrode consisting of a metallic sheet soluble in the electrolyte in the accumulator and a porous material insensitive to alkalis surrounding the sheet.

In testimony whereof I have signed my name to this specification.

ANTOINE MARIUS CAVE. [L. S.]
